UNITED STATES PATENT OFFICE.

HARLAN FAIRBANKS, OF BOSTON, MASSACHUSETTS, ASSIGNOR TO THE
NEW ENGLAND PATENT FIRE ESCAPE COMPANY, OF SAME PLACE.

FIRE-ESCAPE.

SPECIFICATION forming part of Letters Patent No. 277,415, dated May 8, 1883.

Application filed January 22, 1883. (No model.)

To all whom it may concern:

Be it known that I, HARLAN FAIRBANKS, of the city of Boston, in the county of Suffolk and State of Massachusetts, have invented a certain new and useful Improvement in Fire-Escapes; and I do hereby declare that the following is a full, clear, and exact description of the same, reference being had to the accompanying drawings, in which—

10 Figure 1 is a perspective view of the upper end of a fire-escape, showing my improvement. Fig. 2 is a plan of the same laid down flatwise. Fig. 3 is a side elevation of the same. Figs. 4, 5, and 6 are detail views, showing the method of attaching the rounds to the side ropes.

15 My improvement relates to that class of fire-escapes in which a canvas or other flexible spout is employed, extending from the window or other place of exit to the ground.

20 The invention consists in an improved construction of the top of the spout to facilitate entrance to the same, as hereinafter more fully described.

25 In the drawings, A shows the upper end of the flexible canvas spout or conveyer, which extends from the window to the ground.

30 B are rounds or rungs, which connect the two side ropes, C C, at proper intervals apart, and form a ladder above the spout or conveyer. My improvement is as follows:

35 D is a curved iron, made of a piece of gas-pipe or other suitable material, the same being into the form of a half-circle or a segment, and the upper end of the spout being attached thereto by sewing or other means. The sides 40 of the spout at the top have gores, by which the spout is widened at that point sufficiently to fill the width of the curved iron or stay.

45 E E are two double bights of rope or cord, attached to the stay midway between the center and the ends by passing through eyelets of the cloth, thence extending backward, and having eyes a a at their ends, through which a bar or rod is inserted inside the window, resting against and across the window, and thus sustaining the fire-escape.

50 G G are two extensions of the side ropes, C C, which extensions pass up over the ends of the curved iron stay D, being fastened thereto, thence extend backward and downward, and are attached midway of the bights E E, fast thereto. When the ends of the bights are drawn back taut and secured by the bar

aforesaid inside the window, the bottom of the curved stay will strike the front of the window - sill, and the tension will cause the curved stay to stand upright, as shown in Fig. 1, thus distending and opening the mouth of the bag and affording every facility for ready entrance and passage downward of any person who may wish to escape. This effect is produced by the use of the extensions G G, which, when tightened, hold the curved stay in the proper upright position.

Heretofore the upper end of the bag has been held by the side ropes, which were provided with hooks or other attachments, and were drawn inside the window, and in such case the end of the bag hung some distance below the window, and was wrinkled and drawn together, so that no mouth was left open, and it was very difficult to enter. This invention obviates all these difficulties, and opens the mouth of the bag in such a manner that no trouble is experienced in entering the escape, even under the most exciting circumstances.

The rounds or rungs are attached in the following way: The ends of the rounds are turned with grooves b b, Fig. 5. The side ropes, C C, are split or divided, and the ends of the rounds are inserted through the splits till the strands embrace the grooves in the rounds. The natural strain of the ropes bind the rounds; but they are secured in place by 85 windings, c c, of cord on opposite sides of the rounds, as shown in Fig. 6.

Having thus described my invention, what I claim as new, and desire to secure by Letters Patent, is—

In a fire-escape, the combination, with the spout A, of the curved stay D at the upper end thereof, the bights E E, attached to the stay and extending backward, and the extensions G G of the side ropes, passing over 95 the ends of the stay, extending back and attached to the bights, as shown and described, and for the purpose specified.

In witness whereof I have hereunto signed my name in the presence of two subscribing witnesses.

HARLAN FAIRBANKS.

Witnesses:

E. ERNEST CADUC,
GEO. J. MORSE.
